(54) **STEAM ENGINE, ROTARY**

(76) Inventor: **William Jones**

The Schedule referred to in the Letters Patent,
and making part of the same, containing a description in
the words of the said William Jones himself of his in-
vention in the Rotary Steam Engine.

Be it known that I, William Jones of the Town of
Bromford, County of Orange in State of Vermont have
made an improvement in the Rotary Steam Engine, which
is described as follows.

This rotary steam engine consists of the following
principal parts. — The cap or casing. The Steam Wheel
or Chambers. The valves or springs. The Contractor. —
The Liquid Stop. The induction or reduction pipes
for the steam. The side plates.

The Cap or Casing is made of metal, and is made
steam tight by means of packing, placed on each side
of the circle which forms the middle part of the base.
The Steam Chambers in which the valves or floats work,
are formed by means of this casing or side plates to be
hereafter described.

The Steam Wheel is circular & turned perfectly
true & smooth, & of any suitable size. It is divided
into four equal parts more or less, having openings
in them in which the valves work to be hereafter described;
and compartments to receive the springs & the arms for
working them. — This wheel is fixed on a metallic axis,
& is made to work steam tight with side plates. —

The Valves or Springs. The valves are formed by mak-
ing them of the width of the steam wheel & of a suitable
thickness; a notch or opening is made in the outer side
of the valves in which the packing is placed, & a small
plate is secured on the back of just in the valve.

At the inner end of the valve is an arm to which is attached a spring for throwing out the valve against the outer rim or casing. This packing also extends out at the sides of the valves so as to work them tight against the end plates. To the before-mentioned arm is fixed an upright round piece of metal with or without friction rollers, working in the contractor to be hereafter described.

The Contractor. This is formed by making a plate of any convenient size; or it may be cast on the casing. On this plate is made two semi-circles, one of a greater diameter than the other, or falling into each other, meeting exactly or jog.

The Contractor is for working the valves & springs for letting on or off the steam.

A fixed stop, is secured on, or cast on the inner part of the rim or center part of the casing; it is made of the shape of an inclined plane, one end being a further edge to the other a jog or shoulder.

The induction & exhalation pipes, are openings placed in the center rim or casing at about a greater angle apart; one is put near the shoulder of the stop & the other near the further edge of the same.

The side plates are made perfectly true & are secured together with bolts, running them side to side, forming with the center rim completely tight steam chambers.

Operation.

The steam enters at the induction pipe, & passes against one of the movable valves & fixed stop, which carries round the steam wheel till the valves are acted on by the contractor the steam is then let off by the exhalation pipe, this passing a continual

rotary motion of the wheel.

What I claim as my invention is the before described rotary steam engine particularly the springs arms & contractors.

For a further illustration of my invention I refer to the model & Drawing of the same deposited in the Patent office.

In testimony whereof I have hereunto sub-
scribed my name this 1st day of November 1832
